Des. 197,332
Patented Jan. 14, 1964

197,332

HOSE SUPPORTER OR SIMILAR ARTICLE

Richard K. Sutz, Lausanne, Switzerland

Filed Sept. 4, 1962, Ser. No. 71,564

Term of patent 14 years

(Cl. D17—8)

The figure is a front perspective view of a hose supporter or similar article showing my new design.

The back is substantially flat and follows the same outline as the front border.

I claim:

The ornamental design for a hose supporter or similar article, as shown and described.
